UNITED STATES PATENT OFFICE.

MAX C. BATSEL, OF WILKINSBURG, PENNSYLVANIA, ASSIGNOR TO WESTINGHOUSE ELECTRIC & MANUFACTURING COMPANY, A CORPORATION OF PENNSYLVANIA.

WIRELESS RECEIVING CIRCUIT.

Application filed December 11, 1922. Serial No. 606,029.

To all whom it may concern:

Be it known that I, MAX C. BATSEL, a citizen of the United States, and a resident of Wilkinsburg, in the county of Allegheny and

5 State of Pennsylvania, have invented a new and useful Improvement in Wireless Receiving Circuits, of which the following is a specification.

10 My invention relates to wireless receiving systems and, more especially, to the coupling of regenerative vacuum-tube circuits.

15 In its broad aspect, an object of my invention is to provide an arrangement of feed-back circuits embodying a vacuum-tube device which admits of variations in the tuning of one circuit without substantially changing the tendency for said tube to function as an oscillation generator.

20 More specifically, an object of my invention is to provide a regenerative system wherein the regenerative action of the system is independent of the tuning thereof and wherein a uniform change in the degree of feed-back coupling may be obtained without affecting the tuning of said system.

25 Another object of my invention is to provide means whereby a plurality of variometers may be employed for adjusting the tuning and the feed-back relation of a regenerative circuit in accordance with the above-mentioned desired results.

30 In regenerative continuous-wave systems prior to my present invention, the tuning of the system has necessitated simultaneous adjustments in the tickler or feed-back portions of the system to obtain optimum operating conditions.

35 I have found, however, that, by providing a construction comprising a continuously variable tuning reactor and a continuous variable feed-back reactor, which are disposed in a mutually inductive relation, and an auxiliary reactor, which is connected in series-circuit relation with one of said first-mentioned reactors, and tightly coupled to the other, the above-mentioned desired results may be readily obtained.

40 With these and other objects in view, my invention further consists in the details of construction and operation and circuit arrangement hereinafter described and claimed and illustrated in the accompanying drawing, wherein,

45 Figure 1 is a diagrammatic and side ele-

vational view of circuits and apparatus embodying my invention, and

50 Fig. 2 is a detail side elevational view of a modification.

In the embodiment of my invention shown in Fig. 1 of the drawing, a tubular member 1 is provided, at one end, with a winding 2 having spaced portions 3 and 4 constituting the stationary element of a variometer 5. A movable element 6 of the variometer 5 comprises a cylindrical form 7 carrying a winding 8. The form 7 is mounted to rotate within the stationary coil 2 by means of a pivot rod 9 which extends from the form 7 through diametrically opposite points on the tubular member 1. The relatively stationary and movable windings 2 and 8 may be connected in series-circuit relation by means of the rod 9, a spring member 11, and a conductor 12 which terminates at the free end of the stationary winding 2. 75

55 Inductively coupled to the variometer 2 is a second variometer 13 comprising a winding 14 which encircles the other end of said tubular member 1 and which constitutes the stationary winding of the variometer 13. 80 The stationary winding 14 may comprise spaced portions 15 and 16. A movable element for the variometer 13 may comprise a form 17 carrying a winding 18 and is mounted for rotation within the stationary coil 14 by means of a pivot rod 19 extending therefrom through the tubular member 1. As in the case of the variometer 5, the two windings thereof may be connected in series-circuit relation by means of the rod 19, a spring member 21 secured thereto and a conductor 22 which extends to a free terminal of the portion 15 of the winding 14. 85

60 A pair of auxiliary windings 23 and 24 are disposed upon opposite sides of the portions 15 and 16 of the stationary winding 14 of the variometer 13 and immediately adjacent thereto. The windings 23 and 24 are connected in series-circuit relation with the stationary winding of the variometer 2 by 100 means of a conductor 25. The windings 23 and 24 are designed to provide a certain additional degree of coupling between the variometers 5 and 13 over and above that normally existing therebetween by reason of 105 their side-by-side relation, all as hereinafter explained.

65 The free terminal of the rotor winding 8

of the variometer 2 may be connected to an antenna 26 through a condenser 27 while the free terminal of the auxiliary winding 24 may be connected to ground through a conductor 28, to provide a grounded antenna circuit.

A three-electrode tube 29 of customary design has its input electrodes 31 and 32 connected to a point in the antenna circuit intermediate the antenna condenser 27 and the variometer 5 and to ground by means of conductors 33 and 34, respectively, thereby providing a grid circuit including the variometer 5 and the auxiliary stationary coils 23 and 24. The output electrodes 32 and 35 of the tube are connected, by conductors 36 and 37, to the terminals of the variometer 13. The plate circuit, which includes the variometer 13, includes also a source 38 of direct-current energy and a telephone translating device 39.

The equation between the amplifying factor μ of a vacuum-tube device and the several constants of an oscillatory circuit necessary for oscillations to start or to be maintained is

$$\mu = \frac{M}{L} (1 + R_o) \frac{M^2}{LrC}$$

where, as applied to Fig. 1, M is the mutual inductance between the plate and grid circuits by reason of the variometers 5 and 13 and the auxiliary windings 23 and 24; L is the combined self inductance of the tuning variometer 5 and the auxiliary windings 23 and 24; C is the combined effective capacity of the condenser 27 and the antenna 26 to ground; r is the resistance of the variometer 5 and the auxiliary windings 23 and 24; and R_o is the internal resistance of the vacuum tube 29.

From the above relation, it is seen that, in order to cause the tube 29 to have the same degree of regeneration, for various values of the self-inductance L , the value of the mutual inductance M must vary in proper proportion with changes in L . By degree of regeneration is meant the extent to which the losses in the circuits are neutralized by the amplifying action of the tube 29. As hereinbefore stated, this desired result is obtained by providing the additional windings 23 and 24, which are serially included in circuit with the tuning variometer 5 and which are tightly coupled to the windings of the so-called "feed-back" variometer 13, the number of turns of said auxiliary windings being determined by the constants of the circuits and by the geometric arrangement of the various inductors. Hence, the tendency for the tube 29 to oscillate, or the degree of regeneration, when the rotor 17 of the feed-back variometer 13 is in any

fixed position, is independent of the variations in the position of the rotor 6 of the tuning variometer 5.

In order to complete the disclosure of my invention, I shall now describe an exact construction, which has proved satisfactory in practice, though, of course, it is to be expressly understood that my invention, in its broader aspects, is not specifically limited thereto. The main tubular member 1, shown in Fig. 1, is 5½ inches long and 3½ inches in diameter. The rotor forms 7 and 17 are each 1½ inches long and 2½ inches in diameter and are each wound with 38 turns of No. 28 wire. The portions 3 and 4 of the stationary winding 2 each comprise 16 turns of No. 28 wire separated ½ inch. The portions 15 and 16 of the stationary winding 14 comprise two groups of 16 turns of No. 28 wire spaced ½ inch apart. The portions 4 and 15 of the stationary windings are spaced 1½ inches apart. The auxiliary windings 23 and 24 each comprise 6 turns and are spaced ½ inch from the windings 15 and 16, respectively. The capacity of the condenser 27 may vary from approximately 65 to 350 micro microfarads.

In the practical operation of my invention, the rotor 17 of the feed-back variometer 13 is adjusted to the point where maximum intensity of received signals obtains, as indicated by the telephone receivers 39. The rotor 7 of the tuning variometer 5 is then adjusted to bring the system into a condition of resonance with the received signal impulses, the degree of regeneration determined by the position of the rotor 17 remaining substantially constant, all as explained more fully hereinbefore.

The detail construction shown in Fig. 2 is differentiated over that shown in Fig. 1 in the position of the auxiliary windings 23' and 24' in the space intermediate the portions 15' and 16' of the feed-back variometer 13'. The advantage of such arrangement is in the provision of a closer coupling between the several windings than is possible in the construction shown in Fig. 1.

While I have shown only two embodiments of my invention, for the purpose of describing the same and illustrating its principles of operation, it is apparent that various changes and modifications may be made therein without departing from the spirit of my invention. I desire, therefore, that only such limitations shall be imposed thereon as are indicated by the prior art or are specifically set forth in the appended claims.

I claim as my invention:

1. Apparatus comprising a pair of variable inductors disposed in mutual inductive relation and an auxiliary inductor disposed in mutual inductive relation to said pair of variable inductors and included in circuit

125

130

with one of said variable inductors, whereby the mutual inductance of said inductors is a function of the self inductance of said last-mentioned variable inductor.

5 2. A thermionic relay having input and output circuits, variable inductors individual to the respective circuits and disposed in mutual inductive relation to admit of free-back coupling, and means for producing additional feed-back coupling, whereby the degree of regeneration is substantially independent of the tuning of the variable inductor in said input circuit.

15 3. An evacuated electric device having input and output circuits, variable inductors individual to the respective circuits providing feed-back coupling therebetween and means for establishing such additional feed-back coupling that the degree of regeneration is substantially independent of all adjustments of the inductor in said input circuit.

25 4. A receiving system comprising, in combination, a space-discharge device of the three-electrode type having plate and grid circuits, an adjustable tuning inductor included in said grid circuit, an adjustable inductor included in said plate circuit and inductively coupled to said tuning inductor and an additional inductor included in circuit with said tuning inductor and disposed in such mutual inductive relation to said adjustable inductors that the tendency for said device to oscillate is substantially independent of variations in said tuning inductor.

35 5. A space-discharge device of the three-electrode type having plate and grid circuits, a variable tuning inductor included in said grid circuit, a variable inductor included in said plate circuit and inductively coupled to said tuning inductor to provide an adjustable feed-back coupling between said circuits and an inductor serially included in circuit with said tuning inductor and disposed in such inductive relation to said variable inductors that, for any predetermined degree of regeneration, the tendency for said device to oscillate or to be maintained in an oscillatory state is substantially unaffected by variations in the value of said tuning inductor.

45 6. A space-current device having input and output circuits, a variable tuning inductor included in said input circuit, a variable inductor included in said output circuit and inductively coupled to said tuning inductor to provide an adjustable feed-back coupling between said circuits, each of said inductors comprising a pair of relatively movable series-connected coils, and an inductor included in circuit with said tuning inductor and disposed in such inductive relation to said variable inductors that the degree of regeneration is substantially inde-

pendent of variations in said tuning inductor.

7. A space-discharge device having input and output circuits, a variable tuning inductor having a relatively stationary coil and a relatively movable coil serially included in said input circuit, a second variable inductor also having a relatively stationary coil and a relatively movable coil serially included in said output circuit, said stationary coils being mounted in inductive relation to provide feed-back coupling between said circuits, and an inductor included in circuit with said tuning inductor and disposed in relatively close inductive relation to said second variable inductor.

8. A thermionic device having input and output circuits, a variable tuning inductor having a relatively stationary coil and a relatively movable coil serially included in said input circuit, a second variable inductor also having a relatively stationary coil and a relatively movable coil serially included in said output circuit, said stationary coils being mounted in inductive relation to provide feed-back coupling between said circuits and a coil connected in circuit with said tuning inductor and having such degree of coupling with respect to said inductors, that, for any predetermined degree of feed-back coupling, the tendency for said device to oscillate is substantially independent of the variations of said tuning inductor.

9. In a wireless receiving system, a space-discharge device of the three-electrode type having plate and grid circuits, variable inductors individual to each circuit and arranged in inductive relation, each inductor comprising two relatively movable coils in series, an additional inductor connected in series circuit relation with said grid inductor and disposed in such inductive relation with respect to said inductors that the tendency for said device to function as an oscillator remains substantially constant for variations in the value of said grid-circuit inductor, and a work circuit connected in shunt relation to said series connected inductors.

10. Apparatus comprising a pair of variometers, each variometer comprising relatively stationary and movable coils, means for supporting said stationary coils in spaced relation, means for rotatably mounting said movable coils within said stationary coils, an additional stationary winding disposed immediately adjacent to one of said stationary coils and series connected with the others, a space-current device of the three-electrode type having plate and grid circuits, said grid circuit including said additional winding and coils connected in circuit therewith, said plate circuit including the remaining pair of stationary

and movable coils, said additional coil being so coupled to said remaining pair of coils that, for any predetermined position of the variable plate-circuit coil, the degree of regeneration is substantially constant for all positions of the grid circuit coils.

11. As an article of manufacture, a member carrying spaced windings, relatively movable members carrying windings for co-
10 acting, respectively, with said spaced windings, and an additional winding connected in series-circuit relation with one of said spaced windings and disposed immediately adjacent to another.

15 12. As an article of manufacture, a member carrying spaced windings, relatively movable members carrying windings for co-
acting, respectively, with said spaced windings, and an additional winding connected
20 in series-circuit relation with one of said spaced windings, said additional winding comprising spaced portions substantially equally inductively coupled to another of said spaced windings.

25 13. As an article of manufacture, a member carrying spaced windings, relatively movable members carrying windings for co-

acting, respectively, with said spaced windings, and an additional winding connected in series-circuit relation with one of said spaced windings, said additional winding comprising spaced portions carried by said member and disposed upon opposite sides of another of said spaced windings to provide a tight coupling therewith.

14. As an article of manufacture, a member carrying spaced windings, relatively movable members carrying windings for co-
acting, respectively, with said spaced windings, means for causing one of said co-
operating stationary and movable windings to function as a tuning variometer, means
40 for causing another pair of co-operating windings to function as a feed-back variometer and an additional winding connected
45 in series-circuit relation to said tuning variometer and comprising spaced portions tightly coupled to the stationary windings of said feed-back variometer.

In testimony whereof, I have hereunto
50 subscribed my name this 8th day of December 1922.

MAX C. BATSEL.
